UNITED STATES PATENT OFFICE.

FREDERICK C. MARTIN, OF DELPHI, INDIANA.

DESIGN FOR A SPEED BOAT.

Application filed March 17, 1928. Serial No. 25,893. Term of patent 3½ years.

To all whom it may concern:

Be it known that I, FREDERICK C. MARTIN, a citizen of the United States, residing at Delphi, in the county of Carroll and State of Indiana, have invented a new, original, and ornamental Design for Speed Boat, of which the following is a specification, reference being had to the accompanying drawing, forming part thereof.

In the drawings Fig. 1 is a top plan view of the speed boat showing my new design. Fig. 2 is a side elevation thereof. Fig. 3 is an end elevation of the rear thereof.

I claim:

The ornamental design for a speed boat, as shown.

FREDERICK C. MARTIN.
